UNITED STATES PATENT OFFICE.

SAMUEL E. WHITING, OF PORT HURON, MICHIGAN, ASSIGNOR TO
NORTHWESTERN REGISTER COMPANY, OF PORT HURON, MICHIGAN,
A CORPORATION OF MICHIGAN.

DESIGN FOR A REGISTER-HOLDING FRAME.

No. 38,127.

Specification for Design.

Patented July 10, 1906.

Application filed March 14, 1906. Serial No. 306,086. Term of patent 7 years.

To all whom it may concern:

Be it known that I, SAMUEL E. WHITING, a citizen of the United States of America, residing at Port Huron, in the county of St. Clair and State of Michigan, have invented a certain new, original, and ornamental Design for a Register-Holding Frame, of which the following is a specification, reference being had therein to the accompanying drawing, in

which my register-holding frame is shown in perspective.

I claim—

The ornamental design for a register-holding frame, as shown.

SAMUEL E. WHITING.
